UNITED STATES PATENT OFFICE.

ALVINA BRUEGSEMAN, OF ST. LOUIS, MISSOURI.

VAPOR-BATH APPARATUS.

1,080,678.

Specification of Letters Patent.

Patented Dec. 9, 1913.

Application filed March 15, 1913. Serial No. 754,553.

To all whom it may concern:

Be it known that I, ALVINA BRUEGSEMAN, a citizen of the United States, residing at the city of St. Louis, State of Missouri, have 5 invented a certain new and useful Improvement in Vapor-Bath Apparatus, of which the following is a full, clear, and exact description, such as will enable others skilled in the art to which it appertains to make 10 and use the same, reference being had to the accompanying drawings, forming part of this specification, in which—

Figure 1 is a perspective view of a bath tub provided with my improved vapor bath 15 attachment. Fig. 2 is a sectional view on line 2—2 of Fig. 1. Fig. 3 is a detail view of one of the metal clamps.

This invention relates to a new and useful 20 improvement in vapor bath attachment for bath tubs, the object being to enable one to quickly and easily adjust the cover on a bath tub so as to confine the heat in the tub resulting from the presence of hot water and in that way get the benefit of not only the 25 hot water in the tub but the vapor or steam arising therefrom. The water can, of course, be medicated in any desired manner, and after using, the apparatus can be quickly removed from the tub and folded in 30 a compact package to be put away in readiness for future use.

In the drawings, 1 indicates a bath tub of usual or ordinary construction having the outwardly rolling flange around its upper 35 edge as is commonly employed.

2 indicates a sheet of material, preferably of rubber cloth, which is of such size as to fold over the rolling edges of the tub, this sheet being preferably cut to the shape of 40 the tub. On the underside of the sheet and disposed at various points around its marginal edges are elongated pockets 3 for the reception of adjustable clamping hook members 4 shown in Fig. 3. These hook members 45 are slotted at their inner ends for the reception of a bolt whose threaded end receives a butterfly nut 5.

The sheet is split at one end and provided with an opening 6 in the length of the split, 50 which opening is designed to fit snugly around the neck of the person taking a bath. In front of the opening 6 the marginal

edges of the split are preferably folded down and provided with fastening members 7 in the form of glove fasteners so that the 55 person in the tub may readily fasten these downwardly extending marginal edges of the split together. The split portion behind the opening 6 is also provided with fastening devices 8, but in this instance the edges 60 of the split preferably overlap each other, although they may extend downwardly as do the marginal edges in front of the opening 6.

In operation, the hooked clamping members 65 are first adjusted in the pockets and the bolts clasped through the wall of the pockets and the sheet, which openings are preferably protected by metal hollow eyelets so as to prevent the bolt from tearing the sheet 70 and the wall of the pocket. Preferably the hooked clamps are inserted into the pockets sufficiently far so that the sheet will extend down to or beyond the curved ends thereof, as in this manner the sheet is made to 75 closely hug the outrolling flange of the tub. By providing the hooked clamps with slots on each side of the opening 6 permit the person to enter the tub after which the fastening devices 8 may first be secured together and then when the edges of the opening 6 are adjusted around the neck of the 80 bather, the fastening devices 7 may be secured.

The slit in front of the opening 6 is preferably of such length as to enable the person in the tub to reach the faucets either within 90 the tub or outside of the tub, as the case may be, and control the supply of water.

What I claim is:

1. An apparatus of the character described comprising a sheet having pockets 95 disposed around its marginal edge, slotted clamping hooks slidingly arranged in each of said pockets, and a clamping bolt passing through the walls of the pockets and the sheet and through the slots in said clamps 100 to adjustably hold the clamps in position.

2. An apparatus of the character described comprising a sheet, clamping members adjustably secured in pockets to the

marginal edges of said sheet and having curved outer ends, which curved outer ends are also located in said pockets, and means whereby the marginal edges of the sheet are held by said curved clamping ends in close engagement with the outwardly rolling edge of the bath tub.

In testimony whereof I hereunto affix my signature in the presence of two witnesses, this 13th day of March, 1913.

ALVINA BRUEGGEMAN.
